Elisha Johnson, of Rochester, New York.

Setters Patent.

The schedule referred to in these Setters Patent, & making part of the same containing a description in the words of the said Elisha Johnson himself, of his improvement in the construction of Rail Roads.

Be it known that Elisha Johnson of the city of Rochester, county of Monroe and state of New York, have invented new and useful improvements in the construction of Rail Roads, and that the following is a full and exact description of the materials, machinery, form of construction and the mode of executing the work. First. A timber work of the description represented in Fig. 1, prepared and put up in such parts of the line of Rail Road as required and marking a. a. a. blocks of round timber sawed with square ends of any diameter, the most suitable size is 18 inches placed in firm earth by excavating pits or shafts through the roots & vegetable soil and of a proper length to suit the grade line and placed ten feet from centre to centre, in two lines under the line of railing. On these are placed round croptimbers of any size those of 12 inches diameter and nine feet in length the most suitable, these are spotted and fitted to the blocks, places are prepared in the croptimbers 12. to 15 inches in width over the blocks to receive the sleepers marked in place b. b. b. - The longitudinal sills or sleepers to be round timber not less than one foot in diameter at the small end, to be well hewed on the upper side squared at the end, and at each ten feet, and the same placed on the croptimbers and secured by keys marked on place c. c. where the surface is near grade the croptimbers are placed on blocks placed horizontally or laid in trenches in this form all of the line may be timbered excepting the cuttings. This preparation of timber work is made in timbered land while clearing and slashing the line using any description of timber for blocks and croptimbers and for the strings select descriptions for durability in the vicinity

Done in the year 1835

vicinity of the line, and sufficiently straight to admit of the iron
beach surface and to admit the line of track within the flat sur-
face, the roughest description of timber answer for the frame,
and is more secure in the grades; where the surface is near the
grade line the timber is grubbed and the surface ~~marked~~ other
parts of the line where there are embankments, to which are
cut low, and timber moved off, otherwise the surface is left
in its natural state. On the flat surface of the longitudinal timbers
are placed rails of hard timber 8 by 4 inches or of any other size tem-
porarily spiked on. On this timber work is placed four or eight
~~They will be made of the description used for freight cars~~
wheeled carts and designed as a part of the permanent machinery
of the rail road and of the form is common use. The arrangement
of the frame and carts are of a new and particular form
of construction and adapted to the purpose of completing the
excavations and embankments as the work progresses. The carts
at short distances are moved by the labourers and greater by
horse power. The eight wheeled carts are represented by Fig 3 and
have a centre frame and 8 wheels with two boxes 4 by 6 feet and two
feet in height hung by hinges or rivets in the centre of the side pieces
of the frame and are dumped on the outside of the tract and constructed
of 1 $\frac{1}{2}$ and 2 inch plank secured by bolts at the bottom and dovetailed
at one end and open at the other and otherwise secured by spike-
nails. Each end of the centre frame is a square frame with one pair of wheels
secured to the centre frame, by clamps, staples and keys and when
dumped, balances on the axle of the wheels at the pivots and dis-
charges between the rails. The box is secured to the frame between
the wheels. The six wheeled carts have but one end frame and a
small end box hung by hinges to the end piece of the centre frame before de-
scribed. The four wheeled carts consist only of the centre frame in the form
above described and four boxes of 4 by 4 feet and 6 feet in height secured to the side
and end pieces by hinges dumping in the side and center of track, and better adapt-
ed to light cutting and embankments. The carts with the cutting frame are 500
hundred feet apart, drawing placed upon the line of grades. The barrels are
marked

removed and the permanent timber work put down and again prepared as before completing the road as the cutting progress. The rail when any part is completed is used for the removal of materials and for the transportation of goods, persons or property until the embankments are permanent by use and age at which time the temporary rails, ribbons or dealings are taken up, the timber adjusted if settled at any point, the grade particularly prepared, examined, and re-dressed, and the masonry examined or built if temporarily passed over to favor the transportation of the materials by the line of road. Two rails are then put down with care, the iron put on with spike piping through the rails into the longitudinal sills or sleepers, and provision made for piping of the water from the centre of the track at the meeting of the rails, which are proposed to be three by four and a half or five inches of the most suitable timber that can be obtained. The grade to cover one and a half inches over the sleepers or longitudinal sills thereby covering within the grade the whole line of timber work except a part of the nail on which the iron rests and thereby favoring the durability of the timber work. The advantages proposed in the above plan of road ears and mode of construction and executing the work is the improvement claimed and described as follows. First. The application of such timber as is near or in the line of road and in its rough form, and of any strength at small expense, secondly. The use of such timber work for the purpose of grading and the removal of other materials for the construction of the road, and of persons and property in such parts of the line as are completed upon wood (or iron temporarily put on) while the embankments are perfecting, completing the embankments, and cuttings at one third to one half of the expense of any other known mode. Thirdly. Applicable to extending a line of road into, and through swamp districts where pick or dry places where timber has to be removed for the road at great distances as well as with for embankments. Fourthly. The plan proposes that all the timber work (excepting

the ribbons on which the iron lays) becoming, and rendered by the grade and protected in its durability and providing for a continuous bearing of the rail on which the iron lies, removing the difficulty incident to worn roads for locomotive power, and heavy teams, accidents to the machinery presented by a coming in contact with soft timber when thrown from the track, with many other advantages in detail not necessary to enumerate. Fifthly.—A change can be effected in the operation part of, considering a road in the mode proposed; the labour would be controlled and managed by the agent of the company without contractors and the evils incident thereto by employing functionable superintendents (working men) and small parties employed by them in issuing the tasks and constituting other parts of the work with weekly work lists, the progress of construction being similar to working the road after construction, and similar agency and means employed and all of the economy, of rail roads in the transportation of property applied in the removal of the great amount of tonnage required in grading, construction of the masonry and wood work, the saving of labour and nine tenths of the team work, and avoiding the difficulties incident to the increased demand of labour, team work, & manu-
factures and forage are important to the interests of a company and the progress of internal improvement, and is particularly applicable to new districts of territory in the progress of settlement and where limited investments of capital would be necessary.

In comparing this plan with other modes of construction or in
describing other modes to distinguish the mode proposed, first
that all known modes of construction contemplate first grading
of the line by contract or days work by the use of carts teams or
wheel-barrows and in some cases temporary ways with a chain of
temporary earth and piping on the side of earth banks and line
given to a line graded to perfect the banks after which commenced
(and generally the following season) the construction of other parts
of a rail road occupying but three years for the construction
and road touch without any use of the road or benefit of the

the yearly investments. Secondly that in the construction of wood roads a superstructure is formed upon the grade with a thickness from four to five feet apart on which rests the rail secured by keys or wedges leaving no support to the rail between the cross timbers. The ends of the cross timbers and rail and road being above the grade. This form is the modern common use with variations adopting similar principles and the use of small light timber removed and in other cases modes larger hewed timber for rails has been substituted with more substantial roof timbers. Remark. The Tonawanda Rail Academy commencing at city of Rochester. State of New York is now constituting on the plan on which I claim my improvement and is under my direction as chief engineer and is the first road known to have been built or building on any similar plan to which references had to my proposed improvements.
